UNITED STATES PATENT OFFICE.

WILLIAM GLENN McGEE, OF ANDERSON, SOUTH CAROLINA.

UMBRELLA.

SPECIFICATION forming part of Letters Patent No. 634,018, dated October 3, 1899.

Application filed February 16, 1899. Serial No. 705,610. (No model.)

To all whom it may concern:

Be it known that I, WILLIAM GLENN McGEE, a citizen of the United States, residing at Anderson, in the county of Anderson and State of South Carolina, have invented certain new and useful Improvements in Umbrella-Frames, of which the following is a specification.

My invention is an improvement in umbrella-frames; and it consists of a frame having ball-and-socket joints fastening the ribs to the top sleeve in such a way that any one rib may be taken out and replaced and another rib substituted without disturbing any of the other ribs in the sleeve; also of securing the lower ends of the braces to the lower sleeve and the upper ends of the braces to the ribs in the same way.

In the accompanying drawings, Figure 1 is a partial view of an umbrella-frame, the upper and lower sleeves and their attachments being in section. Fig. 2 is a portion of the staff, a sectional view of one of the socket-plates shown in Fig. 3, and of the ball-holding plate shown in Fig. 4 and of the band shown in Fig. 5. Fig. 3 is a face view of an annular socket-plate. Fig. 4 is a face view of an annular ball-holding plate. Fig. 5 is an end view of a ring. Fig. 6 is an inverse view of a clamp for holding one end of an umbrella-brace. Fig. 7 is a view showing one-half of the clamp shown in Fig. 6. Fig. 8 is a view of the brace.

To an ordinary umbrella-staff 1 are secured two annular ball-bearing plates 2. These plates are each provided with a sleeve 3, which sleeve has a shoulder 4, and each plate is provided with a number of slots 5, through which the upper ends of the ribs are permitted to move up and down as the umbrella is opened or closed. Each plate is also provided with a number of ball-bearing sockets 6, that carry the balls 7 on the upper ends of the ribs 8. The ball-bearing sockets 6 are oval-shaped, and the balls 7 are also oval-shaped and exactly fit in their respective sockets, so that the ribs may not turn in their sockets.

Fitting around the shoulder 4 of the plate 2 is an annular ball-holding plate 9, which is provided with a slot 10, passing through its periphery and terminating in an oval-shaped opening 11 just large enough for one of the

oval-shaped balls 7 to pass through. This opening 11 is put immediately over one of the ball-bearing sockets 6 and the ball 7 passed through into said socket 6. Then the plate is turned until the opening 11 is over another socket and a ball passed through into that socket, and then said plate is turned until said opening 11 is over another socket, and so on until all the ribs of the umbrella have been put in, and then said plate 9 is secured from further turning by a screw 12, which passes through a perforation 13 in plate 9 and into a threaded perforation 14 in plate 2. The said plate 9 is held down on the plate 2 by means of a ring 15, which is secured to the sleeve 3 by means of a rivet 16. This rivet may also pass through the staff if desired to hold the said sleeve in place there.

The balls 17 of the braces 18 are held in the lower plate 2 exactly in the same manner as the balls 7 are held in the upper plate 2, and the ring 15 is held to the sleeve 3 by a rivet, as above described, and the balls 17 are put in the sockets of the lower plate and secured therein in the same way that the balls 7 are put in the sockets of the upper plate.

To take any one of the ribs 8 out of the upper sockets or any one of the braces 18 out of the lower sockets, the screw 12 is taken out and the plate, turned until the opening 11 comes over the rib or brace to be removed, and when replaced the plate 9 is turned back to its former position and the screw 12 again put in.

The braces 18 have an oval-shaped ball on each end. The balls on the inner end I have marked 17 and the balls on the outer end I have marked 19.

To each of the ribs 8 is secured a ball-bearing clamp 20. Each one of these clamps is secured to the ribs by rivet 21 and a screw 22 and has a slot 23 in one end terminating in a ball-bearing socket 24. When the said clamp 20 is on the rib, its side 25 is next the staff and the ribs 8 fit in the opening 26. The clamp is first pivoted to the rib by the rivet 21 and then the side 25 is turned down and the ball 19 passed through the opening 26 until it enters the socket 24. Then the side 25 is turned back in place and the clamp 20 secured by means of a screw 22. When it is desired to take the ball 19 out of the clamp

20, the screw 22 is taken out, the side 25 turned down, and the ball slips immediately out of the opening 26.

The lower ball-holding device is provided 5 with an inner sleeve or an extension of sleeve 3, having a slot, so that the umbrella may be held open or shut, as is usual.

Having described my invention, what I claim as new, and desire to secure by Letters 10 Patent, is--

1. In an umbrella-frame the combination with the staff 1 of the ball-bearing plates 2 provided each with a sleeve 3 and a shoulder 4, slots 5, oval-shaped ball-bearing sockets 6, 15 and a threaded perforation 14; annular plate 9 provided with a slot 10, oval-shaped opening 11, perforation 13, and a central opening adapted to fit over shoulder 4 of the plate 2; screw 12 holding said plate 9 from turning; 20 ring 15 fitting around sleeve 3 and adapted to hold plate 9 down on the upper face of plate 2; rivet 16 holding said ring to sleeve 3; ribs 8 provided with oval-shaped balls 7 fitting into oval-shaped ball-bearing sockets 6 of the upper plate; braces 18 having each on one end an oval-shaped ball 17 and on the other an oval-shaped ball 19, said balls 17 25 adapted to fit in ball-bearing sockets 6 of the lower plate; clamp 20 provided with slot 23, 30 ball-bearing socket 24, and opening 26; rivet

21, and screw 22 securing said clamps to the ribs 8, substantially as shown and described and for the purposes set forth.

2. In an umbrella-frame the combination with the staff 1 of the ball-bearing plates 2 provided each with a sleeve 3 and a shoulder 4, slots 5, oval-shaped ball-bearing sockets 6, 35 and a threaded perforation 14; annular plate 9 provided with a slot 10, oval-shaped opening 11, perforation 13, and a central opening 40 adapted to fit over shoulder 4 of plate 2; screw 12 holding said plate 9 from turning; ring 15 fitting around sleeve 3 and adapted to hold plate 9 down on the upper face of plate 2; rivet 16 holding said ring to sleeve 3; 45 ribs 8 provided with oval-shaped balls 7 fitting into oval-shaped ball-bearing sockets 6 of the upper plate; braces 18 having each on one end an oval-shaped ball 17 and on the other an oval-shaped ball 19, said balls 17 50 adapted to fit in ball-bearing sockets 6 of the lower plate; and means for securing balls 19 to the ribs, substantially as shown and described and for the purposes set forth.

In testimony whereof I affix my signature 55 in presence of two witnesses.

WILLIAM GLENN MCGEE.
